Primary Examiner — Elizabeth Albert(74) *Attorney, Agent, or Firm* — Gardner, Linn, Burkhart & Flory, LLP(57) **CLAIM**

The ornamental design for the plant container, as shown and described.

DESCRIPTION

FIG. 1 is a top perspective view of a plant container showing our new design;

FIG. 2 is a right side view thereof;

FIG. 3 is a left side view thereof;

FIG. 4 is a front view thereof;

FIG. 5 is a back view thereof;

FIG. 6 is a top plan view thereof; and,

FIG. 7 is a bottom plan view thereof.

The broken lines in FIGS. 1-7 are included to show portions of the plant container that form no part of the claimed design.

1 Claim, 5 Drawing Sheets---
